CLAIM

The ornamental design for an in-line amplifier, as shown in the accompanying drawings.

DESCRIPTION

FIG. 1 is a perspective view of the in-line amplifier;
FIG. 2 is a front view of the in-line amplifier;
FIG. 3 is a rear view of the in-line amplifier;
FIG. 4 is a bottom plan view of the in-line amplifier;
FIG. 5 is a top plan view of the in-line amplifier;
FIG. 6 is a left side view of the in-line amplifier; and,
FIG. 7 is a right side view of the in-line amplifier.
